UNITED STATES PATENT OFFICE.

JAMES E. FUSSELL, OF ROFF, OKLAHOMA.

FENCE-POST.

1,153,380.

Specification of Letters Patent. Patented Sept. 14, 1915.

Application filed January 30, 1915. Serial No. 5,262.

To all whom it may concern:

Be it known that I, JAMES E. FUSSELL, a citizen of the United States, residing at Roff, in the county of Pontotoc and State of Oklahoma, have invented certain new and useful Improvements in Fence-Posts, of which the following is a specification, reference being had to the accompanying drawings.

This invention relates to new and useful improvements in fence posts and more particularly to a combined fence post and wire fastening device, the main object of the present invention being the provision of a fence post constructed so that it may be readily driven into the ground and securely anchored and, at the same time, is provided with means whereby the fence wires may be quickly and readily fastened to the post and securely held against any lateral or longitudinal movement.

Another object of the present invention is the provision of a fence post of the above character which will possess advantages in points of efficiency and durability, is inexpensive to manufacture and, at the same time, is simple in construction and operation.

With the above and other objects in view, the invention consists in the novel features of construction, combination and arrangement of parts as will be hereinafter referred to and more particularly pointed out in the specification and claim.

In the accompanying drawing forming a part of this application, Figure 1 is a front elevation of a fence post constructed in accordance with my invention, illustrating the relative position of the fence wires with respect to the post. Fig. 2 is a detail perspective view of the post. Fig. 3 is a longitudinal sectional view. Fig. 4 is a transverse section on the line 4-4, Fig. 1; and Fig. 5 is a detail perspective view of one of the securing members.

Referring more particularly to the drawing, the numeral 1 designates a fence post constructed in accordance with my invention and as shown, is substantially hollow in cross section and formed of metal, any desired quality of metal being used. The body of the post is provided on one side thereof with a longitudinal opening 2 which terminates at a point adjacent the upper end thereof and opens out at the lower end thereof. The post is provided at its lower end upon the side

opposite the longitudinal opening with a cut-away portion, as shown at 3 to form the yieldable tongues 4, at the lower end of the post.

From the above it will be apparent that when the fence post is driven in the ground, the pointed ends of the tongues 4 are first engaged within the surface of the earth and as the post is driven downwardly, it will force these tongues 4 to diverge, as shown in Fig. 1 and, after the post has been driven into the ground, the tongues will form a suitable anchor for the same and prevent the post from being easily withdrawn.

The wires of the fence which are generally indicated by the numeral 5 are arranged transversely across the opening 2 in the post and are securely held by means of the fastening members 6 which are U-shaped in form, as clearly illustrated in Fig. 5. The post is provided opposite the opening 2 with a plurality of openings 7 arranged in equal spaced relation so that the ends of the fastening members 6 may be readily inserted through these openings and arranged as illustrated in Fig. 3, so that the fence wires 5 may be placed between the ends of the fastening members 6 and the ends of the fastening members then twisted together as shown in Fig. 3, the twisting operation being carried out until the fence wires 5 are bound tightly against the edges of the opening 2. It will be noted that in cutting an opening in the wall of a cylindrical surface, the outer edges of this opening will engage the fence wires and as the fence wires are forced tightly against this edge, it will securely hold the wires against any longitudinal movement, while the fastening members themselves will securely hold the wires against any lateral movement.

From the above description taken in connection with the accompanying drawing, it will be readily apparent that I have provided a simple and durable fence post which includes, as stated, a cylindrical body having yieldable tongues at its lower end which are normally arranged in parallel spaced relation but as they are driven into the ground, they are forced into divergent relation as shown in Fig. 1 to form suitable anchoring means for the post. The wires of the fence can be quickly and readily fastened in position by first placing the wires

alongside the post so that they extend transversely across the opening 2. The wire fastening members 6 are then inserted through the openings 7 so that the ends thereof project into the opening 2 upon opposite sides of the fence wires. The ends of the members 6 are then twisted together until the fence wires 5 have been bound tightly against the edge of the opening 2. Thus it will be apparent that the fence wires will be securely held against any lateral or longitudinal movement.

The device, as herein shown and described, is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claim.

Having thus described this invention,

what I desire to claim and secure by Letters Patent is:—

As a new article of manufacture, a fence post consisting of a tubular member provided with a relatively long substantially wide elongated open end slot disposed longitudinally of the post substantially the entire length thereof, the open end of the slot being at the lower end of the post, said post being also provided with a longitudinally disposed open slot diametrically opposed to the first mentioned slot, the open end of said second named slot being also at the lower end of the post, said second named slot being of a length materially less than the length of the first named slot, the portions of the post between the slots diverging and being flattened from their inner ends.

In testimony whereof I hereunto affix my signature in the presence of two witnesses.

JAMES E. FUSSELL.
